(57) **CLAIM**

The ornamental design for a tray for dishwasher, as shown and described.

DESCRIPTION

FIG. 1 is a front perspective view of a tray for dishwasher showing our new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof;

FIG. 7 is a bottom plan view thereof;

FIG. 8 is a front perspective view thereof in user environment; and,

FIG. 9 is a front perspective view thereof, illustrating separation of the tray for dishwasher from a lower tray in a user environment.

The broken lines are for environmental purposes only and form no part of the claimed design.
